US00D836114S

(12) **United States Design Patent** (10) **Patent No.:** **US D836,114 S**
(45) **Date of Patent:** **** Dec. 18, 2018**

(54) **POWER ADAPTOR**

(71) Applicant: **eero inc.**, San Francisco, CA (US)

(72) Inventors: **Paul Nangeroni**, San Francisco, CA (US); **Paul Kelley**, San Francisco, CA (US); **Nicholas Reid**, San Francisco, CA (US); **Nathaniel C. Hardison**, San Francisco, CA (US); **Nicholas S. Weaver**, San Francisco, CA (US); **Timothy Amos Schallich**, San Francisco, CA (US)

(73) Assignee: **eero Inc.**, San Francisco, CA (US)

(**) Term: **15 Years**

(21) Appl. No.: **29/583,574**

(22) Filed: **Nov. 7, 2016**

(51) LOC (11) Cl. **14-02**

(52) U.S. Cl. **D14/432**
USPC **433**

(58) **Field of Classification Search**

USPC **433**
CPC **H01M 10/44**

CLAIM

We claim the ornamental design for a power adaptor, as shown and described.

DESCRIPTION

FIG. 1 is an isometric view, from the front right, of the top of the power adaptor;

FIG. 2 is a plan view of the top of the power adaptor;

FIG. 3 is an elevation view of the front of the power adaptor;

FIG. 4 is an elevation view of the right of the power adaptor;

FIG. 5 is an elevation view of the back of the power adaptor;

FIG. 6 is an elevation view of the left of the power adaptor;

FIG. 7 is a plan view of the bottom of the power adaptor; and,

FIG. 8 is an isometric view, from the bottom left, of the back of the power adaptor.

The broken lines represent portions of the structure that form no part of the claim.

1 Claim, 2 Drawing Sheets
